UNITED STATES PATENT OFFICE.

JENS CR. HOLM, OF CAPE SCOTT, BRITISH COLUMBIA, CANADA.

WRENCH.

No. 877,773.

Specification of Letters Patent.

Patented Jan. 28, 1908.

Application filed April 24, 1907. Serial No. 370,109.

To all whom it may concern:

Be it known that I, JENS CR. HOLM, a subject of the King of England, residing at Cape Scott, in the Province of British Columbia, 5 Canada, have invented certain new and useful Improvements in Wrenches, of which the following is a specification, reference being had therein to the accompanying drawings.

The object of this invention is the 10 vision of a wrench which is of simple and strong construction, is easy to adjust, and efficient in operation.

The invention consists in the novel construction, adaptation and combination of 15 parts as will be hereinafter described and illustrated in the drawings, of which Figure 1 is a side elevation of a wrench embodying my invention; Fig. 2, an underside plan view of the same shown partly in section; Fig. 3, 20 a fragmentary upper side plan view; and Fig. 4, a cross sectional view taken through 4-4 of Fig. 3.

In the drawings, the numeral 5 represents a cylindrical frame, or head, having a transverse partition 6 disposed intermediate of its depth and provided with four straight slots 7 and disposed so as to be inclined from planes 25 extending radially of the heads' axis and severally at right angles with the adjacent ones, but parallel to that upon the opposite side of the axis. In the underside of the head and directly below the respective aforesaid slots are recesses 8 severally having a side wall, as 8', parallel with the communicating slots. Positioned within each said recess is a jaw 9 provided with a marginal dovetail 9' which is slidably fitted within a correspondingly formed groove 8" of the above referred to side walls. Rotatably 30 seated upon said partition is a disk, 10 provided with four slots 10' extending spirally from near the center toward the circumference of the disk and arranged to cross the respective slots 7 of the partition. Fixedly 35 secured to each of the jaws and passing through the superpositioned slots is a stud 11 or bolt 11' of which the latter carry washers 12 which are surmounted by butterfly nuts 13 engaging with threads provided 40 upon the bolts and serving to clamp the jaws in adjusted positions. The adjustments of the jaws are simultaneously accom-

plished by imparting an appropriate amount of rotary movement to said disk, whereupon the spiral slots thereof traverse the straight 55 slots of the partition and move the bolts passing therethrough to advance or recede toward or from the middle of the head. To conveniently rotate said disk, it is provided with upwardly protruding lugs 14 adapted 60 to be gripped by the operators fingers. Peripheral ratchet teeth 15 are provided externally of the head as is also a groove 16 above such teeth for the reception of an annular extension 17 of the wrench handle 65 18. This annular portion of the handle is desirably made in two parts which are connected on one side by a hinge 17' and upon the other by a scarf joint 17" secured through the medium of a screw 19, or its equivalent. 70

The handle is provided with a shoulder with faces 18' inclined from the axis of the handle and approximately rectangular of each other and positioned to be opposite said ratchet teeth. Upon each side of the 75 handle is a pawl 20 which are pivotally connected thereto, as by pins 21 passing through the pawls and apertured ears 22 upon the handle.

The pawls are formed with a bend in each 80 and have upon their inner arms and contiguous with the angle of their bends, faces 20' adapted to bear against the respective faces 18' of the handle when the pawls are operatively engaged with the ratchet teeth. 85 The other or tail arms 20" of these members are prolonged to be engaged by springs 23 seated in sockets provided in the handle.

Rotatably mounted upon the handle is a sleeve 25 which is cored out at its end adjacent of the head to furnish a cavity 26 for the housing of either, or both, of the tail-arms 22" as may be required. To allow of the performance of this function the portion of the sleeve about the cavity is provided 90 with spaced notches, as 26', adapted to allow of the tails being pressed thereinto by said springs for causing the faces 20' of the pawls bearing against the angularly disposed faces 18' of the handle. The said sleeve is 95 inferiorly sloped to a sharp edge upon each side of the notches as at 27, whereby the pawl tails are embraced and pressed inwardly through the turning of the sleeve, and by ad-

justing the latter to have either of its notches register with one or the other of the tails, the same is unrestrained and is pressed outwardly by its spring, as before explained.

5 The range of work of a wrench constructed in accordance with this invention is limited by the travel of the jaws and can be used upon bolt heads, nuts, and in fact any piece of work presenting one or more flat 10 faces for engagement and which is capable of entering the space presented between the jaws when in their most distended position. When employed for square nuts or bolts, the gripping faces of all of the jaws may be made 15 in plane surfaces, as at 29, in Fig. 2, while for hexagon or octagon shaped work two of the jaws may advantageously be formed with reentrant gripping faces, as at 29', and in practice, I prefer to embody both of the 20 above described types of jaws in a single wrench, so that its usefulness may be extended.

The operation of the invention, will, it is thought, be understood from the foregoing 25 description. Its advantages reside in the ease of adjustment of its jaws to accommodate itself to various sizes of nuts or bolt heads, through the simultaneous movement of all of the jaws; the engagement of the 30 work upon at least four sides and accordingly is less liable to mar the same even when subjected to a considerable strain; and, furthermore, through the peculiar disposition of the 35 faces of the recesses with respect to the gripping faces of the jaws whereby the outward thrust is resisted by the head and is not dependent upon the clamping screws, thus enabling the wrench to withstand the most severe duty.

40 What I claim as my invention, is—

1. A wrench consisting of a handle, a cylindrical head rotatably mounted in said handle and provided with peripherally disposed ratchet teeth, pawls carried by the 45 handle and adapted to engage said teeth for rotating the head in either direction, the head being provided with slots arranged in rectangular relation and with grooves having one of their respective edges formed with a dovetail slot, jaws reciprocally seated within said grooves, studs secured to said jaws and projecting through said slots of the head, a slotted disk rotatably mounted within the 50 head and engaging said studs within the respective grooves, and means to secure the disk in various rotary positions for clamping the jaws in adjusted condition.

60 2. A wrench consisting of an annular shaped head provided with a slotted partition and formed with recesses in its under side, a disk rotatably seated upon said partition and provided with spirally disposed slots arranged to intersect the respective

slots of the partition, jaws slidably seated in said recesses and having one edge of each engage with a dovetail connection with the side walls of the respective recesses, studs and bolts connected with said jaws and extending through the slots of said partition and disk, nuts engaging said bolts for clamping 65 the disk in various rotary positions, a handle provided with an annular extension which embraces said head, spring pressed pawls pivotally connected to the handle and adapted to engage with teeth provided upon the 70 periphery of the head, and means for controlling the action of said pawls whereby either of them may be predeterminedly retained in inoperative position.

3. A wrench embodying a handle, a cylindrical integral head secured thereto, said head having a central interior partition therein formed with radially disposed slots, a member rotatably mounted on said partition and formed with slots which traverse 80 said slots of the partition, jaws on the opposite side of said partition slidably connected to said head, and studs on said jaws extending through said slots of the partition and member.

90 4. A wrench embodying a handle, a head having annular side walls secured thereto, a partition in said head having slots therein, a disk rotatably mounted on said partition having slots which traverse said slots of the 95 partition, jaws slidably connected to the head on the inner faces of the side walls thereof, bolts secured at one end to the said jaws extending through the said slots of the partition and disk and nuts on some of said 100 bolts to exert pressure on said disk to hold said parts stationary.

5. A wrench embodying a handle, a head secured thereto, a slotted partition in said head midway of its depth, said head beyond 105 one face of said partition having recesses formed in its sides, jaws seating in said recesses and engaging said face of the partition, a disk on the opposite face of said partition having slots which traverse said slots of 110 the partition, studs secured to said jaws and projecting through said slots of the disk and partition, and means on some of the studs to engage said disk and retain the parts in stationary relation.

115 6. A wrench embodying a handle, a head secured thereto, a slotted partition in said head, jaws engaging against one face of said partition, a disk seating on the opposite face of said partition and formed with slots which traverse those of the partition, said head being formed with an annular wall to surround said disk, studs carried by the jaws and extending through said slots of the disk and partition, and means on the disk to enable 120 125 rotation thereof.

7. A wrench embodying a handle, a head secured thereto, a central partition carried by said head and formed with a plurality of radial straight slots, jaws on one face of said partition, a disk on the opposite face of said partition, said disk being formed with a plurality of spiral shaped slots one for each slot of the partition which it traverses, and means on the jaws extending through said slots of the disk and partition. 10
- In testimony whereof I affix my signature in presence of two witnesses.
